UNITED STATES PATENT OFFICE.

ALFRED JABEZ SIMPSON, JR., OF BALTIMORE, MARYLAND, ASSIGNOR OF
ONE-THIRD TO BRENT WATERS, OF BALTIMORE, MARYLAND.

INCANDESCENT GAS-BURNER.

SPECIFICATION forming part of Letters Patent No. 760,930, dated May 24, 1904.

Application filed February 3, 1904. Serial No. 191,882. (No model.)

To all whom it may concern:

Be it known that I, ALFRED JABEZ SIMPSON, Jr., a citizen of the United States, residing at Baltimore, in the State of Maryland, have invented new and useful Improvements in Incandescent Gas-Burners, of which the following is a specification.

This invention relates to incandescent gas-burners; and the primary object of the same is to provide a burner for Welsbach and other incandescent lights with efficient and reliable means for proportionately regulating the supply of gas and air by an adjustment of a valve controlling the admission of gas to the burner or to a mixing-chamber and which simultaneously moves an air-feed-controlling means, whereby the relative quantities of gas and air admitted to the mixing-chamber for producing the best result may be effected without requiring an adjustment of independent mechanism or devices.

A further object of the invention is to prevent smutching or blackening of the mantle of the burner by an irregular or improper admixture of air and gas and also to cause the air to enter the mixing-chamber behind the gas and prevent the burner from lighting back at the point where the gas enters the mixing-chamber.

A further object is to incorporate in a burner organization a series of coacting elements for rendering the burner more practical and including valve devices connected for simultaneous operation, so that when one is opened to admit gas to the burner the other will be closed to prevent the escape of the gas through a pilot-burner, and vice versa.

With these and other objects and advantages in view the invention consists in the construction and arrangement of the several parts, which will be more fully hereinafter set forth.

In the drawings, Figure 1 is a side elevation of a burner embodying the features of the invention and showing a mantle and part of a chimney applied thereto in dotted lines. Fig. 2 is a transverse vertical section through the burner. Fig. 3 is a transverse vertical section through a portion of the burner in a plane at

right angles to that shown by Fig. 2. Fig. 4 is a horizontal section on the line 4-4, Fig. 3. 50

Similar numerals of reference are employed to indicate corresponding parts in the several views.

The numeral 1 designates a gas-inlet plug or coupling bored axially for the passage of gas therethrough and having a screw-threaded terminal for securing the same to a gas-feeding means or supply. The plug or coupling 1 communicates with a tubular T-head 2, having enlargements at opposite sides of the point of communication therewith of the plug or coupling to form valve-seats 3 and 4, the valve-seat 3 being materially larger than the seat 4, and said seats respectively having mounted therein rotatable valves 5 and 6. 65 The valve 5, as shown, has a passage 7 cut therethrough at one side of the center and opening out through the periphery thereof, said passage being straight through the valve, and the valve 6 is formed with an arcuate 70 passage 8, opening through its periphery. The T-head at opposite ends is provided with upwardly-projecting coupling-nipples 9 and 10, the nipple 9 being materially larger than the nipple 10 and having a bore therethrough 75 of the same dimensions as the bore of the plug or coupling 1 and the head 2. The bore of the nipple 10 is reduced proportionately to the bore through a pilot-burner tube 11, which is attached to said nipple and extends upwardly over the lower portion of the mantle applied to the burner proper, the upper end of the tube 11 being fully open to form a pilot-light. The stem 12 of the valve 5 is projected outwardly at one end of the enlargement 3 80 and is secured to the intermediate portion of an operating-lever 13, the end of said lever adjacent to the stem 12 being enlarged and formed with a segmental slot 14, in which a projection 15, eccentrically held by an exterior head 16, connected to the valve 6, loosely projects, the parts being so proportioned that when the lever 13 is operated to open the valve 5 the valve 6 is closed, as shown by Fig. 2. When the lever 13 is operated in a reverse direction to close the valve 5, the valve 85

90 95

6 is opened, the passage 8 in the latter valve being of such length that the gas will be permitted to pass therethrough into the pilot-burner tube 11 before the gas has been fully 5 shut off from the burner proper by the valve 5 in order that the pilot-burner may become ignited and so remain until the burner proper is to be used. The end of the lever 13 opposite that having the segmental slot 14 therein 10 is adapted to have a suitable pull-rod or other analogous device attached thereto, and, as in ordinary constructions of this kind, the pull device may depend from the burner any distance desired.

15 A burner 17 of any approved type to cooperate with an incandescent mantle is used in the present instance and is embraced by a clasp 18, secured to the upper part of the tube 11. This burner has a chimney-supporting 20 rim 19 depending therefrom and an applying-tube 20, which is snugly fitted over a Bunsen tube 21, extending upwardly from the center of an enlargement or mixing-chamber 22 at the lower extremity thereof. A plug 23 is 25 projected upwardly into the chamber 22 through the lower end of the latter and is circumferentially reduced between its opposite ends to form an air-receiving chamber 24, the shell of the chamber 22 being secured to 30 the lower end of the plug by screw-threads, as clearly shown by Figs. 2 and 3. The upper end or head of the plug 23 is reduced to form a partition disk or flange 25, having a series of openings 26 extending vertically 35 therethrough in circular alignment around the center of said partition. The shell of the chamber 22, below the position of the partition 25, is increased in thickness and has a plurality of reduced openings 27 formed therein to provide air-inlets, the air passing through 40 the openings 27 into the chamber 24 and then upwardly through the openings 26 into the mixing-chamber.

Depending centrally from the lower end or 45 head of the plug 23 is a tubular stem 28, having a gas-feeding bore 29 through the upper portion thereof, which gradually reduces at its upper extremity, as at 30, where it passes through the center of the partition formed at 50 the upper end of the plug 23. The lower part of the bore through the stem 28 is screw-threaded, as at 31, and adjustably fitted in the stem and projecting through the plug is a needle-valve 32, having a right-hand screw 55 enlargement 33, engaging the threads 31, and a lower increased left-hand screw enlargement 34, the lower end of the needle-valve being provided with a milled head 35, which is readily accessible for adjusting the valve 60 above the T-head 2. Communicating with the stem 28 above the upper terminal of the threads 31 is a feed-pipe 36, having a screw-plug 37 in its outer end for cleaning purposes and a depending coupling-nipple 38 to receive the upper end of a connecting-pipe 39,

which is attached at its lower end to the nipple 9.

Projecting outwardly from the stem 38 at a point slightly below the lower end or head of the plug 23 are diametrically-opposed guide-arms 40, having vertical openings 41 extending through their outer ends, in which slide-rods 42 have movement and are secured at their lower ends to the opposite extremities of a yoke 43, which engages the left-hand screw 75 enlargement 34 of the needle-valve. The upper ends of the slide-rods 42 are secured in sockets 44 at diametrically opposite points on a controlling-sleeve 45, slidable over the exterior of the lower extremity of the shell of the 80 mixing-chamber 22 and adapted to regulate the open and closed condition of the air-inlet openings 27. By turning the needle-valve 32 in opposite directions it will be adjusted to admit more or less gas into the mixing-chamber 85 22 when the valve 5 is open, and simultaneously with this adjustment of the needle-valve the controlling-sleeve 45 will be moved to regulate a proportionate admission of air into the air-receiving chamber 24. The advantage of this unity of adjustment and control of the admission of air and gas is that the right proportions of both air and gas will be at all times admitted to the mixing-chamber 90 22, it being understood that in the preliminary 95 arrangement of the parts the sleeve 45 and needle-valve will be positioned to obtain a proper admixture of air and gas. Another advantage resident in this simultaneous and proportionate adjustment is the absolute impossibility of admitting more air than necessary and retarding complete combustion and a consequent smutching or blackening of the mantle. By having the gas enter the mixing-chamber ahead of the air ignition of the 100 gas in the mixing-chamber or lighting back is prevented. Furthermore, the adjustment of the needle-valve and the admission of air 105 may be carried on without modifying the flow of gas to the stem 28.

110 The improved burner will be found exceptionally advantageous in use and more economical in the use of gas and mantles.

It will be understood that changes in the proportions, dimensions, and minor details 115 may be resorted to without departing from the spirit of the invention.

Having thus fully described the invention, what is claimed as new is—

1. In a burner of the class set forth, the combination of a burner proper having a coupling and gas-feeding means communicating with the coupling, rotatable valves in a part of the gas-feeding means on opposite sides of the coupling, the one valve having a passage cut 120 straight therethrough at one side of the center and the other valve formed with an arcuate passage which is longer than the passage of the first-named valve, a pilot-burner tube attached to a portion of the gas-feeding means 125 130

and controlled as to its supply of gas by the valve having the longest passage therein, and rigid means directly attached to one valve and loosely connected to the other whereby the 5 said valves will be operated to open one and close the other.

2. In a device of the class set forth, the combination of a burner having gas-feeding means and a connecting-coupling, the gas-feeding 10 means communicating with the coupling, rotatable valves in a part of the feeding means on opposite sides of the coupling, the said valves differing in diameter and the smaller one having a longer passage therein than the 15 larger one, a lever directly attached to one valve and having a slotted end connected to the other valve and operative to open one valve and close the other, and a pilot-burner tube connected to the gas-feeding means and 20 controlled as to the supply of gas thereto by the smaller valve.

3. In a device of the class set forth, a burner proper, a Bunsen tube over which such burner proper is fitted, the said Bunsen tube 25 having a lower enlargement to form a mixing-chamber provided with air-inlet openings, a plug fitted in the mixing-chamber and having a depending stem, a needle-valve adjustable in the plug, a controlling-sleeve slidably 30 mounted on the shell of the mixing-chamber to regulate the open and closed condition of the air-inlet openings, said sleeve being simultaneously operated with the adjustment of the valve, and gas-feeding means connected 35 to the said stem.

4. In a device of the class set forth, the combination of a burner proper, a Bunsen tube on which said burner proper is fitted, said tube having a lower mixing-chamber with air- 40 inlet openings, a plug in the lower part of the mixing-chamber having a bore communicating with the latter, a needle-valve in the plug, a controlling means movable over the air-inlet openings and connected to the lower 45 portion of and simultaneously adjustable with the movement of the said needle-valve, and gas-feeding means for the burner.

5. A burner of the class set forth, having gas-feeding means and air-inlet openings, a 50 needle-valve adjustable to control the supply of gas to the burner, and a controlling device operating in conjunction with the air-inlet openings and having means engaging and vertically movable on a part of the needle-valve, said controlling device being connected to and simultaneously adjustable with the needle-valve whereby the admission of gas and air to the burner may be uniformly maintained in proper proportions.

6. A burner of the class set forth having a 55 mixing-chamber provided with air-inlet openings, a tubular plug fitted in said mixing-chamber and having an upper perforate partition above the said inlet-openings, a needle-valve adjustably disposed in the plug, a con-

trolling device slideable over the openings and connected to the needle-valve for simultaneous adjustment with the latter, and gas-feeding means attached to the plug.

7. A burner of the class set forth having a 70 Bunsen tube with an enlarged extremity to form an upper mixing-chamber and a lower air-receiving chamber, the lower portion of said extremity having air-inlet openings therein, an annular plug fitted in the lower portion 75 of said extremity and having a perforate head between the air-inlet openings and the mixing-chamber, the said plug having a bore therethrough, gas-feeding means connected to said plug, a needle-valve adjustably disposed in the plug, and a movable controlling device on the mixing-chamber to open and close the air-inlet openings, said controlling device being connected to and simultaneously adjustable with the needle-valve.

8. A burner of the class set forth having a Bunsen tube with an enlarged extremity provided with air-inlet openings, a plug mounted in said extremity and having a bore therethrough and a perforate partition at one end 90 to separate the air-inlets from a portion of said extremity, the plug having a stem with a bore partially provided with screw-threads, a gas-feeding means connecting with said stem, a needle-valve adjustably mounted in the stem 95 and plug and having right and left screw-thread enlargements thereon, the right screw-thread enlargement engaging the threads of the stem, and means on the left screw-threaded enlargement of the needle-valve connected to 100 a sliding sleeve on the enlarged extremity of the Bunsen tube to control the open and closed condition of the air-inlet openings, said sleeve being simultaneously adjustable with and proportionately to the adjustment of the needle-valve.

9. In a device of the class set forth, a burner having air-supply means and a gas-feeding conduit, a valve operating in connection with said conduit having a depending stem, and a 110 controlling means movable in relation to the air-supply means and having a device engaging and movable on the said stem, and simultaneously adjustable with the movement of the said valve.

10. A burner having air-supply openings and gas-feeding means, a needle-valve movable in relation to the said gas-feeding means and having right and left screw-threads on portions thereof, a controlling-sleeve slidably 120 mounted in relation to the air-supply openings, and connecting devices between the said sleeve and the needle-valve and operative by a part of the screw-threads of the latter.

11. A burner having air-supply openings 125 and gas-feeding means, the latter including a tubular stem, a needle-valve disposed in the stem and having right and left screw-threaded portions, the right screw-threaded portion engaging the stem, a sleeve slideable over the 130

air-supply openings, a yoke engaging the left screw-threaded portion of the needle-valve, and connecting-rods between the terminals of the yoke and the sleeve.

- 5 12. A burner having air-inlet openings and gas-feeding means including a depending stem with outwardly-projecting guide-lugs thereon, a needle-valve disposed in the said stem and having right and left screw-thread portions, the left screw-thread portion engaging the stem, a sleeve slidable over the air-inlet

openings, a yoke engaging the left screw-thread portion of the needle-valve, and connecting-rods attached to the terminals of the yoke and to the sleeve and movable through 15 the said lugs.

In testimony whereof I affix my signature in presence of two witnesses.
